METHOD OF PROVIDING FOR INTERNAL
ATMOSPHERIC EXPANSION OF FILLED
BAGS AND HERMETICALLY SEALING
SAMERobert Morris Bergstein, Cincinnati, Ohio, as
signor to Edna May Bergstein and himself, as
trustees

Application March 4, 1937, Serial No. 129,010

23 Claims. (CL. 93—6)

5 My invention relates to a mode of sealing the open end of bags having contents therein, said bags being made of substantially impervious flexible material preferably heat sealable on the interior surface at least, all seams of which are hermetically sealed.

This application is related to my application Serial Number 95,124 filed August 10th, 1936, and is intended to cover among other things the 10 method divided out of said application. The disclosure herein illustrates the method which may be carried out by the mechanism described in said application, as well as the method that can be carried out by the mechanism described 15 in my co-pending application, Serial No. 131,738 filed March 18, 1937 or by other mechanical means or by hand manipulation.

The results which I produce in accordance 20 with the method herein described, which can be carried out either by hand or by machine, is to reduce the atmospheric volume within the bag coincident with closing it and prior to effecting the final seal, then to produce the seal by uniting hermetically portions of the two opposite mouth walls in a face to face relationship 25 with no folds intervening therebetween, to produce an air-tight liquid-tight seam, providing space for internal atmospheric expansion within the sealed bag thereafter. I thus provide a direct 30 face to face fusion between the interior surfaces of said walls by heat, to produce a seam that is integral with the interior surface of the bag material itself.

Another object of my invention is to cause a 35 curving on straight line of a limited portion of said flattened area, extending entirely across said flattened area, to produce an assured face to face contact in said curving, and while in said curved position to apply heat to said curved portion. In this way I am able to avoid any pressure during the sealing operation above that which will bring about a contact and thus avoid the danger of a poor seal when the bag sealing 40 material is very soft from heat applied to it.

45 A still further object of my invention is to locate the seam or seams uniting said two opposite walls of bag mouth above the line where said two bag walls come together in flattened relationship, so that the internal atmosphere of 50 bag has room thereafter to expand by filling out the flattened portion of bag below said seam.

55 And a still further object of my invention is to accomplish all the foregoing either in bags alone, or in bags which are used as liners of cartons, and in the event of bags being used

as a liner of carton, to further provide for a partial inward drawing of the opposite walls of the bag liner below the upper edges of the main body of the carton, so that after the sealing flaps of the carton has been closed over the 5 sealed bag liner, the atmosphere within the sealed bag can expand to the extent permitted by the flattened portion of said bag liner within the interior of the carton, which bag has been sealed, and the bag material itself can expand 10 to the limit permitted by the enclosing carton without bulging it.

Other objects of this invention will appear as the description of the invention proceeds.

In my co-pending application, Serial No. 15 66,650 filed March 2, 1936, I described a bag made of substantially impervious material, the inner surface of which is heat fusible, which surface is integrally united at all seams, no re-entrant folds being interposed between said 20 joints so that the walls can be integrally united without pin holes which would be formed at infolded ends of reentrant folds, resulting in said 25 seams being leak-proof and air-tight. Such a bag independently or as the inner liner of a 30 carton, can be used for purposes of retaining liquids or gases, an accomplishment not heretofore attained in bags or flexible containers. To retain these same properties in the bag after 35 it has been filled with contents and mouth sealed, it is necessary of course that the mouth be sealed just as effectively as the remaining bag 40 joints, namely: by an air-tight and liquid-tight closure, or else the other properties of the sealed bag would be lost. None of the bag-sealing methods in the present state of the art is capable 45 of accomplishing this.

A mere fusion together of the entire mouth of a bag as has been proposed heretofore would not be adaptable to my type of bag for the 50 following reasons:

(1) If such an air-tight closure should be made on my type of bag, the atmosphere, having no means of escape, would be entrapped within the sealed bag mouth, permitting no folding 45 manipulations or turning over of the mouth after being sealed.

(2) With the atmosphere entrapped or enclosed to the full limit permitted by the sealed bag, any increase in atmospheric volume for 50 any of a variety of causes such as gases given off by the contents, or the effect of higher temperatures, etc., would have thrown a severe strain on the bag so that in most cases a leakage would occur or the bag would burst.

Now by my method as herein described an air-tight and liquid-tight final seam is made after the contents have been inserted, so that the sealing joint is as effective as other joints and the protection provided by the finished package is substantially equal to that of the bag material itself, and this is further done in such a manner that an internal expansible area is allowed within the sealed bag, to compensate for an increase in the internal atmospheric volume. That I accomplish by sealing a zone above the apexes of the divergent triangles of the collapsed bag mouth.

In the drawings:

15 Figure 1 is a perspective of an open bag having the contents therein.

Fig. 2 is a fragmentary perspective of the bag shown in Fig. 1 with the mouth thereof in spread position.

20 Fig. 3 is a fragmentary perspective of the bag after the operation of flattening the mouth has been performed.

Fig. 4 is a fragmentary perspective illustrating the seal extending across the upstanding mouth 25 of the bag.

Fig. 5 illustrates an alternative method of forming the seal wherein the flattened portion of the bag is turned at a right angle to the position shown in Fig. 4 before the sealing operation is 30 performed.

Fig. 6 illustrates a bag or liner within a paper-board carton, the said bag or liner having been subjected to a spreading and a flattening operation and the flattened mouth of the bag sealed 35 while in upstanding position.

Fig. 7 is a perspective similar to Fig. 6 except that the sealing of the flattened mouth has been performed with the flattened portion in a turned down position.

40 Fig. 8 is a sectional view through the flattened mouth portion of a bag or liner and shows therewith a means for accomplishing the seal.

Fig. 8a illustrates an optional way of making a seal.

45 Fig. 9 shows one way of closing the end flaps of the carton.

Figs. 10 and 11 illustrate another and perhaps preferable way of closing the end flaps of the carton.

50 Fig. 12 is a section along line 12-12 of Fig. 11.

Fig. 13 is a sectional view taken through two plies of heat sealable material showing a seal formed therebetween.

In my two above referred to applications, I 55 have shown mechanism of various kinds for making the desired seal, and for distending the bag mouth and wiping the walls of the bag together. My present application is directed to the method of the aforesaid applications, and contemplates 60 either machine or hand operations.

As illustrated by the diagrams, my invention is capable of a considerable variety of expressions. For example, considering first an independent bag 1, with contents therein as shown in Fig. 1, and having its inner lining at least of a readily heat fusible material, the mouth is elongated, or extended as by mechanical fingers or by hand as in Fig. 2. Then the two opposite walls are flattened together as by mechanical sweepers. The 65 base of the completely flattened portion 2 may either be directly on the contents level or above the contents level with the slight tapering from the base of the flattened portion to the contents level itself. This second step brings the two 70 halves of the bag mouth flat together as shown

in Fig. 3, and incidentally squeezes out air from the bag mouth.

Thereafter, while retained in flattened position, a fusion is effected between the interior surfaces of the two walls in flat face to face relationship, over a desired restricted portion of the area, said seam or line of fusion being located above the apexes of the extending triangles formed incidental to the flattening of the mouth. As shown in Fig. 4 this seal is made by deflecting 10 the bag walls into a curve thus obtaining complete contact and applying heat at the line of bend as at 3.

These steps can be carried out either by hand tools or by machine, and while the bag is at rest 15 or in motion. It is also a matter of choice as to whether the sealing is done while the flattened portion is in upright position, or whether the flattened portion is retained in flattened condition and folded to a desired angle as shown at 4 20 in Fig. 5, and thereafter sealed as at 6 in the same manner as described. It is also a matter of option as to whether the heat sealed joint be effected immediately following the sweeping together to flatten the walls, or as part of the operation which folds over the flattened portion to an angle, or whether this be accomplished as a subsequent step either while the flattened portion is upright or folded at any angle. If desired, a means can be employed in several successive 25 steps of the operation, either to form independent heat sealed seams, or to operate successively on the same seam portion.

A common factor in all variations, however, is that the walls of the mouth are brought together 35 in flattened relationship, and while retained in said flattened relationship the transverse face to face seam is made, said seam being located above the apexes of the triangles formed incidental to the flattening, so that after having been 40 sealed the internal atmosphere within the bag can expand by filling the flattened portion below the line of sealing; also the seal is much more effective if made at a bent zone.

In a hand operation a channel plate 2a can 45 be placed at one side of the walls 2 and a heated edge tool 2b placed against the opposite side of the wall 2 and sufficiently advanced to effect a slight pushing of the bag material into the channel but without any pressure applied to the channelled plate through the bag material. Or else as in Fig. 8a, the deflected zone can be established by turning the projecting bag mouth by a guide 50 20, so that it curves over a heated plate 21, or else applying radiant heat to the curved portion. 55

The requirement for accomplishing the same result when the bag is used as a liner for a carton is much the same. The main additional feature is that the flattening of the extending upper walls of the mouth should also include a partial 60 flattening of these bag walls within the main body of the carton itself. This is desirable so that when the flaps of the carton have been sealed or closed, with the sealed bag mouth inside the carton, the atmospheric volume within 65 the sealed bag can expand by filling the flattened portion below the bag seal, and there will also be sufficient area available in the sealed carton to permit expansion of the bag area itself within the limits permitted by the enclosing carton without bulging the latter.

The handling of the carton flaps themselves form no part of my invention, and can be folded or manipulated in any of the number of ways now known in the present state of the art, just 75

so they are in a non-obstructing position for the operations on the bag mouth. As illustrated in Fig. 9 of the drawings, when the seal 5 is accomplished while the flattened portion 6 of the bag mouth is in upright position one of the side flaps 7 of the carton 8 can be folded in first, then the opposite pair of flaps 9, which will bring in with them the extending triangular portions of the bag liner, and then the final flap 10 can be folded over, with no direct manipulation of the bag mouth liner itself being required. When the sealed bag mouth liner is folded to right angles so that it lies substantially within the plane bounded by the upper edges of the main body of the carton as indicated at 11 in Fig. 7, the flaps can be folded in the order just described, also by folding inwardly of the flaps 9, as shown in Fig. 10 the extending triangular portions 12 of the bag liner can be folded in prior to folding over the two side flaps 10. Preferably there is no direct manipulation of the sealed mouth of the bag liner, as the normal folding and closing procedure of the carton flaps themselves serves to close or fold the bag material properly.

The essential feature of my invention in regard to the seal itself is the flat face to face uniting of two opposite bag walls, by means of heat applied to a predetermined portion of the flattened area preferably applied without pressure except sufficient to form the curved zone with no folds intervening therebetween, so that the seam becomes integral with the interior surface of the bag itself. The portion to be so united is located preferably well above the apexes of the triangles formed incidental to the flattening, for the further reason that directly at the apexes of these triangles small wrinkled or infolded bag portions are likely to occur, and any such wrinkles or infolds or additional thicknesses of material prevent an effective face to face fusion required to obtain a hermetical closure.

My preferred method of effecting the closure by bringing a desired portion of the two flat adjoining surfaces together in a curved or arched relationship is to assure a positive contact between the interiors of the two walls without substantial pressure, and while in said curved position to apply heat to the curved zone.

I preferably accomplish this curved relationship between the two adjoining flattened surfaces by means of a tongued element and a corresponding grooved element, which in maximum operative relation do not actually contact but which have a tolerance or clearance therebetween to avoid the distortion of the heat softened inner surfaces which would be caused by actual pressing.

As illustrated in my application illustrating automatic machine the tongue and groove element may be either part of the sweepers used to flatten the extending walls of the bag, or part of the means used to fold over the flattened mouth of the bag, in either of which cases the tongue and groove come together to within the small tolerance mentioned above, and while in said operative position heat is applied to the curved portion of the two flattened walls. In another mechanism the bag is retained in flattened position and a portion passed between a stationary tongue and groove element, heat being applied during its passage through said element.

The curvature secures a positive contact between the interior surfaces of the two adjoining wall portions, and it is very important to note

that according to my invention there is not actually any positive pressure applied, since there is always a tolerance between the tongue and slotted element, the reason being that pressure of any sort applied after heating, might distort the freshly softened interior portions and so prevent the desired hermetically fused seam.

I have not attempted to illustrate particular carton shapes or bag types in this specification. My novel method will apply to a wide variety of structures and in the claims that follow I wish to express the novel features of my method itself apart from particular forms or particular mechanical devices.

Having thus described my invention, which I claim as new and desire to secure by Letters Patent is:—

1. A method of sealing bags whereby space is provided for internal expansion after final sealing which consists in collapsing the bag mouth and applying heat thereto in a zone located above the initial contact of the mouth walls a distance sufficient to accommodate fluid expansion within the bag.

2. A method of sealing bags whereby space is provided for internal expansion after final sealing which consists in collapsing the bag mouth and applying heat thereto in a zone located above the initial contact of the mouth walls, said zone being established by curving the bag mouth without substantial pressure during heat application.

3. A method of making air- and liquid-tight closure seams on the open end of a filled bag which consists of reducing the atmospheric volume within the interior by flattening together the opposite walls above the contents thereof, causing a curving of said flattened walls on at least one straight line, said line located above the apexes of the triangles formed due to the flattening of said walls, and while in curved position causing heat to be applied to the curved zone to result in a face to face fusion of the inner surfaces of walls substantially defined by said curvature, the spacing of said fused line being sufficiently spaced above said apexes to accommodate fluid expansion within the bag.

4. A method of providing space for atmospheric expansion within the interior of an hermetically sealed bag which consists of flattening the walls of said open mouth of bag after same has been filled with contents, thus causing a lessening of atmospheric volume within the interior of said bag, and when in flattened position sealing the upper portion only of said flattened walls.

5. A method of making a liquid-tight and air-tight seal in a filled bag having a heat fusible interior surface, consisting of flattening the open mouth causing the opposite walls to be brought face to face, causing a line of curvature across a predetermined portion of the flattened area above the peak of the triangles formed incidental to said flattening, and while in curved position to cause a fusion of the inner surfaces at said line of curvature by means of heat, said fused line being sufficiently spaced above said apexes to accommodate the subsequent internal expansion within the bag.

6. A method of making a liquid-tight and air-tight seal in a filled bag having a heat fusible interior surface, consisting of flattening the open mouth causing the opposite walls to be brought face to face without reentrant folds, causing a line of curvature across a predetermined portion of the flattened area above the peak of the

triangles formed incidental to said flattening, and while in curved position to cause a fusion of the inner surfaces at said line of curvature by means of heat, said fused line being sufficiently spaced above said apexes to accommodate the subsequent internal expansion within the bag.

7. A method of sealing the open mouth of a material containing bag consisting of bringing together in flattened relationship the two opposite walls of said mouth, and thereafter uniting the interior surfaces of said two opposite walls by means of heat over a predetermined limited portion of said flattened area spaced away from the initial line of contact of the walls so as to provide a substantial expansion zone in the bag above the material therein.

8. A method of closing the mouth of a bag made of substantially impervious material having contents therein, which consists of bringing together in flattened position two opposite walls of said mouth and while in flattened position effecting an air-tight seal above the base of the flattened portion, sufficiently to permit the subsequent expansion within the sealed bag.

25 9. A method of closing the mouth of a bag made of substantially impervious material having contents therein, which consists of bringing together in flattened position two opposite walls of said mouth with no reentrant folds intervening and while in flattened position effecting an air-tight seal above the base of the flattened portion, sufficiently to permit the subsequent expansion within the sealed bag.

35 10. A method of sealing an extending mouth of a bag made of substantially impervious material heat sealable on the interior at least which consists of effecting a flattened relationship between two opposite sides of said mouth with no additional thickness of material intervening, and while 40 maintaining said flattened relationship bringing about a seal between said sides by heat, said seal being positioned sufficiently above the base of the flattened area to permit the subsequent atmospheric expansion within the heat sealed bag.

45 11. A method of sealing an extending mouth of a bag made of substantially impervious material heat sealable on the interior at least which consists of effecting a flattened relationship between two opposite sides of said mouth with no additional thickness of material intervening, and while 50 maintaining said flattened relationship bringing about a seal between said sides by heat, said seal being positioned sufficiently above the base of the flattened area to permit the subsequent atmospheric expansion within the heat sealed bag, and said seal being made by bringing a portion of the flattened area, extending entirely across the flattened area but at a distance above the base of said area, into curved relationship on a straight 55 line, to assure positive contact incident to said curving, and applying heat to said portion while in curved relationship to effect a fused hermetical seal.

60 12. A method of closing the mouth of a bag made of substantially impervious material having contents therein, which consists of bringing together in flattened position two opposite walls of said mouth and while in flattened position effecting an air-tight seal at a distance above the base of the flattened portion, sufficiently to permit the subsequent expansion within the sealed bag and thereafter folding said flattened portion while retaining in flattened position and effecting an hermetical seal.

75 13. A method of closing the mouth of a bag

made of substantially impervious material having contents therein, which consists of bringing together in flattened relation two opposite walls of said mouth and while in flattened relation effecting an air-tight seal above the base of the flattened portion, to permit expansion within the sealed bag and thereafter folding said flattened portion while retaining in flattened position effecting an hermetical seal, said seal being made by bringing a zone above the base of the flattened portion into arched condition and applying heat to the said area substantially defined by the arc.

14. A method of sealing hermetically the open mouth of a bag made of relatively impervious material, heat sealable on the interior at least, and with seams integrally united, whereby opposite walls of mouth are flattened with no folds intervening between said walls, and applying heat sufficiently above the juncture of said walls to fuse interior integrally, to thus provide space for the subsequent atmospheric expansion internally by means of the distending of the flattened area below the line defined by the seal.

15. A method of sealing the open mouth of a liner made of substantially impervious material, heat sealable on the interior at least and projecting from an end of a carton enclosing body portion of said liner, said carton having closing flaps attached to said end, which consists of bringing opposite liner walls together in fully flattened condition, and also to cause a partial flattening of said walls on the interior of main body of said carton, and while retaining the liner mouth in said condition effecting a face to face hermetical seal between said flattened walls above the apexes of triangular portions of liner formed incident to said flattening, whereby internal atmosphere within sealed liner is sufficiently reduced to permit the sealed mouth to be readily foldable into the body of carton, whereby after the closing flaps of carton are secured the internal atmosphere can expand the partially flattened liner walls to the extent permitted by the expansion of the fully flattened portion below line of sealing.

16. A method of sealing the open mouth of a liner made of substantially impervious material joined hermetically at all seams, the body of said liner being enclosed within a carton having closing flaps adjacent to open end thereof, said open mouth projecting from said open end of carton, consisting of bringing opposite side mouth walls into flattened contact causing a graduated taper of said walls from their lower line of contact to a point below the top edges of the carton, and while in said position effecting an hermetic closure between walls along a line a substantial distance above said lower line of contact, whereby the free flattened mouth walls may subsequently expand into the space provided by said taper within the carton.

17. A method of sealing the extending open mouth of a liner the main portion of which is enclosed in an outer carton, said carton having closing flaps attached to edges of the open end adjacent to the open mouth of the liner, which consists of causing the complete flattening together of the opposite walls of liner mouth, and partial flattening of said walls within the main body of carton, thereafter effecting an hermetic seal a distance sufficiently above the base of the completely flattened area that the expandable area within the sealed liner can expand to the extent that the cubic content of the main body of the carton will permit.

18. A method of sealing the open mouth of a

liner whose body is enclosed in an outer carton which consists in reducing the atmospheric volume of the liner prior to the sealing and thereupon sealing said liner so that the surface area of the liner below the line of sealing is substantially equal at least to the internal area of the carton body, and potential volumetric content within said sealed liner substantially equal to the cubic volume of the carton body, to provide space for expansion of the flattened evacuated bag area below liner seal to the limit permitted by said enclosing carton.

19. A method of sealing the open top of a contents containing liner whose body is enclosed within a carton having flaps appended to its open end, and which consists in securing said liner body to the main carton body a sufficient distance below the upper edge of the main carton body to allow for bag expansion, then drawing together opposite walls of said open top of liner so that said walls extend in a graduated taper to the joint securing the main body of the liner to the main body of the carton, and then sealing the said walls to each other with a substantial flattened portion below the seal.

20. A method of sealing a package comprising an outer carton having closing flaps adjacent to open end and enclosed within the body of carton a liner having its open mouth extending beyond main body of carton intermediate said closing flaps which consists of folding said closing flaps outwardly, elongating the top of the liner and sweeping said elongated walls together in flattened position, causing a partial contraction of said walls within the main body of the carton, thereafter bringing a section of the flattened walls above the apexes of the triangular portions formed incidental to said flattening, into curved position in a substantially straight line extending completely across the flattened portion and ap-

plying heat to said curved section while so curved thereafter folding sealed liner top substantially into plane defined by upper edges of main body of carton, folding said carton closing and flaps inwardly to overlie said sealed liner top and thereafter securing said carton closing flaps together.

21. A method of sealing a package comprising an outer carton having closing flaps adjacent to open end and enclosed within the body of carton a liner having its open mouth extending beyond main body of carton intermediate said closing flaps which consists of folding said closing flaps outwardly, elongating the top of the liner and sweeping said elongated walls together in flattened position, causing a partial contraction of said walls within the main body of the carton, thereafter bringing a section of the flattened walls above the apexes of the triangular portions formed incidental to said flattening, into curved position in a substantially straight line extending completely across the flattened area and applying heat to said curved section while so curved thereafter folding inwardly one set of opposite closing flaps of said carton, and then folding inwardly the opposite pair of closing flaps and then securing said flaps together.

22. A method of sealing the open mouth of a filled bag which consists of bringing together in flattened position two opposite walls of the bag mouth, and applying heat in two successive steps to a predetermined portion of said flattened area.

23. The method of forming a closing seam in the open mouth of a filled bag, the interior of said mouth at least being heat fusible which consists in flattening together opposite walls of said bag, deflecting a portion of said walls, and while so deflected applying heat substantially confined to the deflected portion.

DISCLAIMER

2,114,623.—*Robert Morris Bergstein*, Cincinnati, Ohio. METHOD OF PROVIDING FOR INTERNAL ATMOSPHERIC EXPANSION OF FILLED BAGS AND HERMETICALLY SEALING SAME. Patent dated April 19, 1938. Disclaimer filed June 12, 1939, by the patentee and Edna May Bergstein, as trustees.

Hereby enters this disclaimer as to claims 1, 4, 7, and 8 of said Letters Patent as follows:

As to claim 1, hereby disclaim from the method claimed any step of collapsing the bag mouth which does not include mechanical pressure applied from both sides to the outside of the bag mouth.

As to claim 4, hereby disclaim from the method claimed, any step of flattening the walls of the open mouth which does not include mechanical pressure applied from both sides to the outside of the bag mouth.

As to claim 7, hereby disclaim from the method claimed, any step of bringing together in flattened relationship of the two opposite walls of said mouth, which does not include mechanical pressure applied from both sides to the outside of the bag mouth walls.

As to claim 8, hereby disclaim from the method claimed, any step of bringing together in flattened position, the two opposite walls of said mouth, which does not include mechanical pressure applied from both sides to the outside of the bag mouth walls.

[Official Gazette July 18, 1939.]

liner whose body is enclosed in an outer carton which consists in reducing the atmospheric volume of the liner prior to the sealing and thereupon sealing said liner so that the surface area of the liner below the line of sealing is substantially equal at least to the internal area of the carton body, and potential volumetric content within said sealed liner substantially equal to the cubic volume of the carton body, to provide space for expansion of the flattened evacuated bag area below liner seal to the limit permitted by said enclosing carton.

19. A method of sealing the open top of a contents containing liner whose body is enclosed within a carton having flaps appended to its open end, and which consists in securing said liner body to the main carton body a sufficient distance below the upper edge of the main carton body to allow for bag expansion, then drawing together opposite walls of said open top of liner so that said walls extend in a graduated taper to the joint securing the main body of the liner to the main body of the carton, and then sealing the said walls to each other with a substantial flattened portion below the seal.

20. A method of sealing a package comprising an outer carton having closing flaps adjacent to open end and enclosed within the body of carton a liner having its open mouth extending beyond main body of carton intermediate said closing flaps which consists of folding said closing flaps outwardly, elongating the top of the liner and sweeping said elongated walls together in flattened position, causing a partial contraction of said walls within the main body of the carton, thereafter bringing a section of the flattened walls above the apexes of the triangular portions formed incidental to said flattening, into curved position in a substantially straight line extending completely across the flattened portion and ap-

plying heat to said curved section while so curved thereafter folding sealed liner top substantially into plane defined by upper edges of main body of carton, folding said carton closing and flaps inwardly to overlie said sealed liner top and thereafter securing said carton closing flaps together.

21. A method of sealing a package comprising an outer carton having closing flaps adjacent to open end and enclosed within the body of carton a liner having its open mouth extending beyond main body of carton intermediate said closing flaps which consists of folding said closing flaps outwardly, elongating the top of the liner and sweeping said elongated walls together in flattened position, causing a partial contraction of said walls within the main body of the carton, thereafter bringing a section of the flattened walls above the apexes of the triangular portions formed incidental to said flattening, into curved position in a substantially straight line extending completely across the flattened area and applying heat to said curved section while so curved thereafter folding inwardly one set of opposite closing flaps of said carton, and then folding inwardly the opposite pair of closing flaps and then securing said flaps together.

22. A method of sealing the open mouth of a filled bag which consists of bringing together in flattened position two opposite walls of the bag mouth, and applying heat in two successive steps to a predetermined portion of said flattened area.

23. The method of forming a closing seam in the open mouth of a filled bag, the interior of said mouth at least being heat fusible which consists in flattening together opposite walls of said bag, deflecting a portion of said walls, and while so deflected applying heat substantially confined to the deflected portion.
